UNITED STATES PATENT OFFICE.

THOMAS R. McKNIGHT, OF AURORA, ILLINOIS, ASSIGNOR TO THE WESTERN WHEELED SCRAPER COMPANY, OF AURORA, ILLINOIS, A CORPORATION OF ILLINOIS.

DUMP-WAGON.

SPECIFICATION forming part of Letters Patent No. 773,093, dated October 25, 1904.

Application filed July 27, 1904. Serial No. 218,394. (No model.)

To all whom it may concern:

Be it known that I, THOMAS R. McKNIGHT, a citizen of the United States, and a resident of Aurora, in the county of Kane and State 5 of Illinois, have invented certain new and useful improvements in Dump-Wagons, of which the following is a specification, reference being had to the accompanying drawings.

My invention relates to dump-wagons; and 10 its principal object is to provide a new and improved means for suspending the swinging doors from the wagon-body in such way that when the doors are allowed to open to dump the load the outer edges of the doors will 15 swing outward and upward around and outside of the lower edges of the sides of the wagon-body, so as to insure a complete and perfect dumping of the load.

To this end my invention consists, broadly, 20 in applying to said doors a curved bar or loop, which is preferably formed of steel or suitable material and which is secured to the doors in such a way as to extend from the outer edge of the door and engage a suitable bearing mounted in the side of the wagon-body.

My invention also has for an object the improving of dumping-wagons in sundry details hereinafter set forth.

In the accompanying drawings, Figure 1 is 30 a top or plan view of the wagon. Fig. 2 is a vertical section on line 2 2 of Fig. 1. Fig. 3 is a rear end view of the wagon with a part of the end removed to show the construction and showing the doors closed. Fig. 4 is an 35 end view of the wagon, showing the doors open in the position in which they normally hang when allowed to freely drop. Fig. 5 is an enlarged detail, being an isometric view of one of the plates mounted in the side of the 40 wagon-body to support the roller-bearing. Fig. 6 is an enlarged detail, being a side view of the pawl-and-ratchet mechanism for opening and closing the doors. Fig. 7 is an enlarged detail, being a top or plan view of the 45 parts shown in Fig. 6; and Fig. 8 is a cross-section showing a modification of the form of the curved bars or loops and a different method of attaching the lifting-chains to the doors.

Referring to the drawings, 9 indicates a wagon-body, consisting of sides 10, front and 50 end boards 11 12, and swinging bottom doors 13 14. The wagon-body is mounted in any approved way upon wheels 15 16. The side-boards 10 are provided with forward extensions 17, extending forward over the front 55 wheels 15 and supporting a seat 18.

19 indicates curved bars or loops, which, as best shown in Figs. 3 and 4, are of a general U-shaped construction. In the form of construction shown in Figs. 3 and 4 the inner 60 ends of the loops 19 are bolted to the tops of the doors 13 14, respectively, on the inside of the wagon, and the other ends of the loops 19 pass around outside of the outer edges of the doors 13 14 and are secured below the doors 65 by being bolted to angle-irons 20, which are bolted or otherwise appropriately secured to the bottoms of the doors 13 14. The loops 19 pass through suitable slots or openings 21 in the sides 10 of the wagon-body. As is best 70 shown in Figs. 1 and 2, there are two of these loops 19 upon each side of the wagon, and this is the preferable construction, although, if needed, more or less of said loops could be used upon each side.

75 Referring to Fig. 5, 22 indicates a plate which is provided with a bent-in portion 23. One of these plates is mounted upon each side of each of the slots or openings 21, with the projection 23 inserted in said slot. The projection 23 is provided with a suitable opening 24. The plates 23 thus form bearings for rollers 25, which are journaled in the openings 24. The curved bars or loops 19 engage the rollers 25, which thus form a bearing upon 85 which the loops 19 move when the doors are opened or closed.

When the doors are allowed to drop, they swing into and remain normally in the position shown in Fig. 4, the loops 19 passing over 90 and bearing upon the rollers 25. It will be seen that the construction is such that in swinging into this position the outer edges of the doors will pass outward and upward around the lower edges of the side-boards and outside 95 of the same substantially in the position

- shown in Fig. 4, and this is the position which they will assume if allowed to merely drop of their own weight. When, however, the wagon contains a load and the doors are allowed to open to permit the dumping of the load, there will be a side thrust upon the doors caused by the falling load, which will cause the doors to swing into the position shown in dotted lines in Fig. 4 while the load is being dumped.
- 10 When the load is emptied, the doors will swing again into substantially the position shown in Fig. 4 and normally hang in that position until the doors are closed by the mechanism hereinafter described.
- 15 Referring particularly to Figs. 1, 6, and 7, 26 indicates a shaft or pipe roller which is journaled in the projecting portion 17 of the side 10 in any approved way, with its ends projecting out through the sides upon each side 20 of the wagon, as is best shown in Fig. 1. 27 indicates chains one end of which is secured to the projecting ends of the shaft 26 in such a way as to be wound upon said shaft when the shaft is rotated, as hereinafter described.
- 25 The chains 27 extend backward to substantially the center of the wagon-body proper and pass around rollers 28, which are mounted in suitable bearings 29 on the sides of the wagon in any well-known and approved manner, and 30 thence passing through the sides of the wagon-body, through suitable openings therein, cross each other and are secured to the upper surfaces of the doors 13 14, near the inner edges thereof, as is best shown in Fig. 3.
- 35 Referring particularly to Figs. 6 and 7, 30 indicates a hand-lever which is keyed or otherwise secured to the shaft 26 and is provided with a pawl 31, which is operated by a bell-crank lever 32, pivoted upon the lever 30 40 and link 33. 34 indicates a ratchet-wheel which is keyed or otherwise secured to the shaft 26 beside the lever 30 and is adapted to be engaged by the pawl 31. To rotate the shaft 26, so as to raise the doors, the lever 30 45 is lifted, the pawl sliding over the teeth of the ratchet-wheel 34. When the lever is lowered, the pawl 31 engages the teeth of the ratchet-wheel 34 and rotates the same, rotating with it the shaft 26 and winding the chains 50 27 thereon until the doors are raised into their closed position. 35 indicates a lever which is pivotally mounted on the side extension 17 and carries pivoted upon it a pawl 36. These parts normally rest in the position shown in 55 Fig. 6, with the pawl 36 engaging the teeth of the ratchet-wheel 34, preventing its backward rotation and holding the doors in the position to which they have been raised by the operation of the hand-lever 30. The cen- 60 ters upon which the pawl 36 and lever 35 are pivoted are in such relation to the teeth of the ratchet-wheel that, as is shown in Fig. 6, the pressure of the ratchet-wheel 34 against the pawl 36 will not lift the same. When it is 65 desired to dump the load, the hand-lever 35 is raised until the center upon which the pawl 36 is mounted passes upward of the line of force exerted by the ratchet-wheel 34, whereupon by the pressure of the ratchet-wheel 34 the lever 35 will be further lifted and the 70 pawl 36 will drop, disengaging it from the teeth of the ratchet-wheel 34 and allowing the shaft 26 to freely rotate under the weight of the load to swing the doors open and discharge the load. When the load is discharged, 75 the lever 35 and pawl 36 are placed in the position shown in Figs. 6 and 7 by hand and the lever 30 operated to lift the doors. By the crossing of the chains 27, as shown in 80 Figs. 3 and 4, when the doors are lifted into their closed position the action of the crossed chains is such as to prevent the doors 13 14 and the loops 19 from sliding outward under the pressure of the load.
- In the modification shown in Fig. 8 the 85 wagon-body, with its end-boards, side-boards, and swinging doors, is the same as above described, said parts being indicated by corresponding numbers, as are also the rollers 25 and the parts in which they are mounted, the 90 same description as heretofore given applying to all of said parts. 37 indicates the loops or curved bars, which in this construction are secured below the bottoms of the doors 13 14 and passing upward and outward around the 95 outside edges of said doors curve upward and inward such a distance as to terminate inside of the wagon-body in a downward-projecting stop 38 at their inner ends. The curved portions of the loops or curved bars 37 engage with 100 and bear upon the rollers 25 in the same manner as before, and the curve is substantially the same as above described, the difference being that the loop is an open one and does not extend inward and downward, so as to be secured to 105 the inner or upper surface of the doors, and is provided with stops 38, which engage the rollers 25 when the rollers are in their closed position in such a way as to prevent any further outward movement of the loops 37, and hence 110 prevent any outward sliding of the doors 13 14 when in their closed position. In this case, as is shown in Fig. 8, it is not necessary to cross the chains 27, and their inner ends may 115 be secured near the inner edges of the doors, which are respectively upon the same side of the wagon-body as the chains. When the doors in this modification are allowed to open, as above described, they will swing into and ultimately remain in the same position as is 120 shown in Fig. 4, and under the side thrust of the load will temporarily swing into substantially the same position as the doors shown in dotted lines in Fig. 4.
- That which I claim as my invention, and 125 desire to secure by Letters Patent, is—
1. The combination with a wagon-body, and a door adapted to swing into and out of operative position under said wagon-body, of a traveling pivotal connection between the 130

outer edge of said door and said wagon-body, substantially as described.

2. The combination with a wagon-body, and a door adapted to swing into and out of operative position under said wagon-body, of a traveling pivotal connection between the outer edge of said door and said wagon-body, and adapted to normally suspend said door with its outer edge outside of said wagon-

10 body, substantially as described.

3. The combination with a wagon-body, and a door adapted to swing into and out of operative position under said wagon-body, of a traveling pivotal connection between the outer edge of said door and said wagon-body, and adapted to normally suspend said door with its outer edge outside of said wagon-body, and means for moving said door into, and retaining it in, its closed position until

20 released, substantially as described.

4. The combination with a wagon-body, a bearing on the side of said wagon-body, and a door adapted to swing into and out of operative position under said wagon-body, of a loop secured to said door and extending from the outer edge thereof upward and then inward to engage said bearing, substantially as described.

5. The combination with a wagon-body, a bearing on the side of said wagon-body, and a door adapted to swing into and out of operative position under said wagon-body, of a loop secured to said door and extending from the outer edge thereof upward and then inward to engage said bearing, and means for moving said door into, and retaining it in, its closed position until released, substantially as described.

6. The combination with a wagon-body, a bearing on the side of said wagon-body, and a door adapted to swing into and out of operative position under said wagon-body, of a loop secured to said door and extending from the outer edge thereof upward and then inward to engage said bearing, and means adapted to prevent said door from sliding outward when in its closed position, substantially as described.

7. The combination with a wagon-body, a bearing on the side of said wagon-body, and a door adapted to swing into and out of operative position under said wagon-body, of a loop secured to said door and extending from the outer edge thereof upward and then inward to engage said bearing, means for moving said door into, and retaining it in, its closed position until released, and means adapted to prevent said door from sliding outward when in its closed position, substantially as described.

8. The combination with a wagon-body, a bearing on the side of said wagon-body, and a door adapted to swing into and out of operative position under said wagon-body, of a

loop secured to said door and extending from the outer edge thereof upward and then inward to engage said bearing, means for moving said door into, and retaining it in, its closed position until released, and a stop on said loop adapted to engage said bearing and to prevent said door from sliding outward when in its closed position, substantially as described.

9. The combination with a wagon-body, a bearing on the side thereof, and a door adapted to swing into and out of operative position under said wagon-body, of a curved bar secured at one end to the door and extending from the outer edge of said door upward and then inward to engage said bearing, and means for lifting said door to close the bottom of said wagon-body and retain the same in place until released, substantially as described.

10. The combination with a wagon-body, a bearing on the side thereof, and a door adapted to swing into and out of operative position under said wagon-body, of a curved bar secured at one end to the door and extending from the outer edge of said door upward and then inward to engage said bearing, whereby when said door is allowed to drop the outer edge will pass outward and upward outside of said wagon-body and will normally hang in said position, and means for lifting said door to close the bottom of said wagon-body and retain the same in place until released, substantially as described.

11. The combination with a wagon-body, and bearings in the sides of said wagon-body, doors hung below said wagon-body and adapted to be moved into their closed position with their inner edges meeting, and means for moving said doors into, and retaining them in, their closed position until released, of curved bars secured at one end to the doors and extending from the outer edges of said doors upward and then inward to engage said bearings, whereby when said doors are allowed to drop the outer edges thereof will pass outward and upward outside of said wagon-body and will normally hang in said position, substantially as described.

12. The combination with a wagon-body, a slot in the side thereof, a roller journaled in said slot, a door adapted to be swung into and out of operative position below said wagon-body, and means for moving said door into its closed position, of a curved bar secured to said door and extending from the outer edge thereof outward and upward, and then inward and upward, and adapted to engage and move upon said roller, and means for preventing said door from sliding out when in its closed position, substantially as described.
